UNITED STATES PATENT OFFICE

162,634

SOAP HOLDER

Arthur E. Du Bois, Fort Lauderdale, Fla.

Application July 11, 1949, Serial No. 3,834

Term of patent 3½ years

(Cl. D4—3)

To all whom it may concern:

Be it known that I, Arthur E. Du Bois, a citizen of the United States and a resident of Fort Lauderdale, in the county of Broward and State of Florida, have invented a new, original, and ornamental Design for a Soap Holder, of which the following is the specification, reference being had to the accompanying drawings, in which:

Figure 1 is a perspective, side elevational view of a soap holder, showing my new design;

Figure 2 is a plan view thereof;

Figure 3 is a side elevational view of the soap holder;

Figure 4 is a front elevational view thereof; and

Figure 5 is a bottom plan view thereof.

The dominant features of my design reside in that portion shown in full lines in the drawing.

I claim:

The ornamental design for a soap holder, substantially as shown and described.

ARTHUR E. DU BOIS.
